UNITED STATES PATENT OFFICE.

CONRAD A. WINTERS, OF ANACONDA, MONTANA.

CLEANER FOR CONVEYER-BELTS.

1,239,066.

Specification of Letters Patent.

Patented Sept. 4, 1917.

Application filed July 27, 1916. Serial No. 111,694.

To all whom it may concern:

Be it known that I, CONRAD A. WINTERS, a citizen of the United States, residing at Anaconda, in the county of Deerlodge and 5 State of Montana, have invented a new and useful Cleaner for Conveyer-Belts, of which the following is a specification.

This invention relates to cleaners for conveyer belts, and its object is to provide a 10 structure for the purpose which may be applied to a conveyer belt without the necessity of additional mechanism or disturbing any part of the installed structure.

In accordance with the present invention 15 there is provided a basic structure carrying a driving pulley and a beater device, permanently connected together and arranged for attachment to a machine having a conveyer belt in such manner as to both support 20 and beat the under run of the conveyer belt, thus removing therefrom any accumulations which may cling to the active surface of the belt. The basic portion of the cleaner is so arranged that the drive pulley and beating 25 structure of the beater may be adjusted with respect to the lower run of the belt to engage the belt with sufficient frictional force.

The invention will be best understood 30 from a consideration of the following detailed description, taken in connection with the accompanying drawings forming part of this specification, with the further understanding that while the drawings show a practical form of the invention, the latter is 35 not confined to any strict conformity with the showing of the drawings, but may be changed and modified so long as such changes and modifications come within the scope of the appended claims.

40 In the drawings:—

Figure 1 is a side elevation of a portion of the conveyer belt and the beater structure associated therewith.

Fig. 2 is a plan view of the structure 45 shown in Fig. 1.

Fig. 3 is an elevation of the structure shown in Fig. 1 as seen from the right hand end thereof.

Fig. 4 is an end elevation of the beater 50 drum.

Referring to the drawings there is shown a portion of a conveyer belt 1 and a drum 2 around which the conveyer belt is carried, and this drum may represent the end 55 drum where the conveyer belt discharges. The drum 2 is mounted on a shaft 3 sup-

ported in journal bearings 4 after the usual manner.

The cleaner structure is provided with a base plate 5 which, when installed, is secured in any suitable manner to a fixed part 60 of the structure and located beneath the lower run of the conveyer belt at the discharge end of the conveyer belt. The base plate 5 is formed with an inclined or wedge-shaped portion 6 supporting another wedge-shaped portion 7, which in turn carries a plate 8. The base plate 5 and the plate 8 65 may correspond in size and are held together, but at the same time permitted to 70 approach or recede, by bolts or guide pins 9 permitting such approach or recession of the two plates as may be needed. The wedge 6 is or may be fast to the plate 5, while the wedge 7 is capable of movement 75 both with relation to the wedge 6 and plate 8. The movement of the wedge 7 is brought about by screw rods 10 passed through and capable of rotating in lugs 11 at one end of the base plate 5. The rods 10 are held 80 against longitudinal movement by collars 12 engaging the lugs 11, and are threaded into the wedges 7, so that on turning the rods 10 the wedges 7 are moved lengthwise 85 of the wedges 5 and coact with the latter to raise the plate 8 or permit it to drop in accordance with the direction of movement of the wedge 7. By providing the structure 90 with two screw rods 10 near opposite sides, and if need be with two sets of wedges 6 and 7, the plate 8 may be raised or lowered at will with regularity by turning the rods 10 simultaneously.

Mounted on opposite sides of the plate 8 near one end are standards 13, while other 95 similar standards 14 are carried by the opposite end of the plate 8.

The standards 13 carry at their upper ends, since they are upright in the installed position, a shaft 15 carrying a roller or 100 pulley 16. The shaft 15 also has fast thereto at one end of the roller a beveled pinion 17.

The standards 14 carry at their upper ends a shaft 18 on which is mounted a drum 105 19. The shaft 18 also carries a bevel pinion 20. The plate 8 between the standards 13 and 14 on one side of the plate supports an 110 upstanding bearing block 21 having journal bearings 22 at its upper end through which there is passed a shaft 23 having bevel pinions 24, 25 on respectively opposite ends,

these pinions meshing with the pinions 15 and 20, respectively. The result of this arrangement is that when the pulley 16 is turned in one direction the drum 19 receives 5 rotative movement in the opposite direction through the intermediary of the pinion 17, shaft 23 and pinion 20.

The drum 19 is shown as of polygonal cross-section, although such shape is not 10 obligatory. Mounted on and extending lengthwise of the drum 19 are angle brackets 26 each carrying a pair of plates or strips 27, 28, by means of bolts 29. Clamped between the plates 27 and 28 are strips 30 of 15 suitable flexible material, such, for instance, as rubber belting, the plates 27 and 28 being customarily of steel. The flexible strips 30 are held between the plates 27 and 28 except at their outer edges, where they have 20 some flexibility because there unsupported.

When the device is applied to a conveyer belt, the pulley 16 is so positioned as to engage the then under surface of the lower run of the conveyer belt. With the parts 25 properly positioned, the pulley 16 is engaged by the lower run of the conveyer belt and with the latter in motion the pulley 16 is rotated by the traveling conveyer belt. The strips 30, which serve as beater strips 30 on the drum 19 constituting the beater drum, successively strike the lower run of the conveyer belt on that surface which in 35 the upper run constitutes the receiving surface of the conveyer belt. The direction of movement of the beaters with respect to the conveyer belt is opposite to the direction of movement of the under run of the conveyer belt, wherefore the beaters strike the belt with suitable force to dislodge any particles 40 clinging thereto and, moving oppositely to the direction of movement of the conveyer belt, such dislodged particles are driven away from the belt in a manner to become entirely free from the belt.

45 The action of the beater blades is relatively rapid and violent with a rubbing or sweeping motion in addition to the impact of the elastic portions of the blades of the beater upon the conveyer belt.

50 The drive of the beater drum is positive through the gearing and connecting shafting, while the pulley 16 receives motion directly from the conveyer belt itself. The degree of pressure exerted by the pulley 55 against the conveyer belt may be determined by the movement of the wedge 7 on the wedge 6, and while such movement may be participated in by the beater drum, the latter may be so proportioned with relation 60 to the pulley 16 that the proper degree of impact is maintained. The force of the impact, however, will vary with the speed.

The beater drum may have its main or hub portion of cast iron, the beater blades 65 of rubber belting and the clamping strips

one of steel plate and the other of steel spring, which latter in the direction of rotation of the beater drum serves as an elastic backing strip permitting further yielding of the exposed portion of the rubber belting. 70 By this means the first impact on the rubber belting is more or less yielding and while the spring strip represented by the plate 27 is also more or less yielding, its degree of yielding is less than that of the rubber belting, thus yieldingly backing up the rubber belting and stiffening the force of the impact. 75

The entire cleaner structure may be independent of any part of the conveyer structure and constitute an attachment thereto, so that it is susceptible of separate manufacture and subsequent attachment to the conveyer structure. Of course, in a new machine the belt cleaner may be built into the 80 machine, but it is also capable of being separately built and attached to existing machines without the necessity of any change whatever in the latter and without the necessity of any connections or additional devices for driving it. Moreover, the entire belt structure is entirely beneath the lower 85 run of the conveyer belt and assists in keeping the latter from sagging. 90

While the means shown in the drawing 95 for adjusting the drive pulley and beater structure toward and from the under run of the belt have been described in detail, it is to be understood that the invention is not confined to the use of such particular adjusting means, for there are various other 100 adjusting means, some of well known construction, and in common use, which may be used for the purpose.

What is claimed is:—

1. A cleaner for conveyer belts, comprising a basic structure individual to the cleaner, a pulley mounted on the basic structure and adapted to engage the under surface of the lower run of the conveyer belt, a 110 beater structure also mounted on the basic structure and provided with beaters for engaging the under surface of the under run of the conveyer belt, and driving connections between the pulleys and beaters. 115

2. A cleaner for conveyer belts, comprising a basic structure individual to the cleaner and composed of superposed parts with means for controlling the separation of the parts, a pulley mounted on the higher 120 part and adapted to engage the under surface of the lower run of the conveyer belt, and a beater mounted on the higher part of the basic structure and connected to the pulley to be driven by the latter. 125

3. A cleaner for conveyer belts, comprising a basic structure composed of superposed parts with means for controlling the separation of the parts, a pulley mounted on 130 the higher part and adapted to engage the

under surface of the lower run of the conveyer belt, and a beater mounted on the higher part of the basic structure and connected to the pulley to be driven by the latter, the beater comprising a series of blades of flexible material with backing strips of flexible material tending to return the blades to their normal position after being displaced therefrom by engagement with the conveyer belt.

4. A cleaner for conveyer belts, comprising a drive pulley for engaging the under surface of the lower run of a conveyer belt, a beater structure connected to the drive pulley for actuation thereby, and a basic member individual to the cleaner and carrying both the pulley and beater and provided with means for the adjustment of the pulley and beater toward and from the under surface of the lower run of the conveyer belt.

5. A cleaner for conveyer belts, comprising a supporting structure adapted to be placed beneath the lower run of a conveyer belt, said cleaner having a pulley adapted to engage the under surface of the lower run of the conveyer belt for actuation thereby, and a rotative beater connected to the pulley to be driven by the latter, the beater being provided with beater blades of flexible material with each blade having a backing of spring material adapted to yield to the impact of the blade on the conveyer belt and to return the blade to normal position after leaving the conveyer belt.

35 6. A cleaner for conveyer belts comprising

ing a basic structure composed of superposed members with intervening wedge surfaces and means for the relative adjustment of the surfaces to raise and lower the upper member, a drive pulley on the upper member 40 adapted to engage the under surface of the lower run in the conveyer belt, and a beater structure also on the upper member of the basic structure, said beater structure being connected to the pulley for actuation 45 thereby.

7. A cleaner for conveyer belts, comprising a basic structure composed of superposed members with intervening wedge surfaces, and means for the relative adjustment 50 of the surfaces to raise and lower the upper member, a drive pulley on the upper member adapted to engage the under surface of the lower run in the conveyer belt, and a beater structure also on the upper member of the 55 basic structure, said beater structure being connected to the pulley for actuation thereby, the connections between the pulley and conveyer structure comprising positive gear connections for rotating the beater structure 60 in a direction opposite to the direction of rotation of the pulley.

In testimony, that I claim the foregoing as my own, I have hereto affixed my signature in the presence of two witnesses.
